UNITED STATES PATENT OFFICE.

WILLIAM J. DE WITT, OF AUBURN, NEW YORK.

HOLLOW SHOE FORM.

Application filed June 16, 1925. Serial No. 37,486.

This invention pertains to footwear and more particularly to a hollow shell or form useful during certain stages of the process of manufacturing footwear as a substitute for the usual last and also for maintaining the lasted shape of a shoe or other article of footwear during transportation and while on exhibition as well as between intervals of use.

5 In accordance with an improved process of manufacture which I have devised I withdraw the usual last from the shoe or other article of footwear at some intermediate stage in the operation, for example, when 10 making McKay shoes directly after the lasting operation is completed; and during the subsequent stages of manufacture, and also if desired up to the sale of the shoe to the ultimate consumer, I maintain the original 15 lasted shape of the shoe by means other than the last, for example, by the use of a hollow thin walled shell or form having an outer contour substantially like that of the last and adapted to keep the upper plumped out 20 and free from wrinkles.

Such a form may in accordance with my process above outlined be placed upon the last prior to the lasting operation, the upper being lasted over the form and the last afterward withdrawn leaving the form within the shoe, or alternatively the shoe may be lasted directly upon the last and after withdrawal of the last the form may be inserted in its place.

30 In order to fulfil its function as a substitute for the usual last the form must fill the shoe to the same extent as the last and must be capable of affording very substantial resistance to inward crushing and distortion.

35 In order that such a form may be useful in the practice of my improved process, wherein the form remains in the shoe during the bottoming operations, it must be open at the bottom so as to avoid 40 interference with such operations; it should have thin walls so as to vary but little in its outer contour from the contour of the last in substitution for which it is used; it should be resilient so that it will not break 45 readily when subjected to blows; it should be cheap to manufacture and capable of being made to conform with exactitude to the shoe last; it should not interfere with the withdrawal of the last from the shoe, and 50 itself should be readily removable from the finished shoe; it should be light in weight.

55 and little subject to the action of moisture at ordinary temperatures; and it should not be injurious to the fabrics of which shoes are made.

While particularly useful in performing the shoe manufacturing process above referred to I find that forms having in general the above characteristics have further utility. For example such forms with slight, if any 60 modification, in shape or construction may be employed as trees to keep shoes plumped out during intervals of use or while on exhibition; they may, if not employed as lasts during the early stages of manufacture of 65 the shoe, be inserted during subsequent operations to keep the linings clean; and in the manufacture of shoes from materials which are easily soiled or damaged these forms or shells may be placed upon the outside of the 70 upper to protect the upper from dirt or injury. In the latter event I contemplate the use of any suitable fastener means for securing them in position or the actual lasting in 75 with the edges of the form with the upper and the subsequent cutting away of the 80 forms from the finished shoe.

In making the present invention it has been my object to provide a hollow shell or 85 form having the above characteristics desirable in a form intended for the various uses suggested, and in the accompanying drawings I have illustrated by way of example a preferred form together with certain modifications thereof.

90 In the accompanying drawings Fig. 1 is a plan view to small scale of my improved form;

Fig. 2 is a side elevation thereof; the form shown in Figs. 1 and 2 being particularly intended for use as a last during the shoe making process;

Fig. 3 is a transverse section to larger scale substantially on the line 3—3 of Fig. 1;

Fig. 4 is a side elevation of a modified 100 form;

Fig. 5 is a bottom plan view of a still further modification; and

Fig. 6 illustrates the improved form in position for insertion into or withdrawal 105 from a shoe.

Referring to Figs. 1, 2, and 3, the numeral 1 indicates the form as a whole, such form comprising the forepart 2, the heel part 3, the cone 4 and the throat portion 5.

110 While this form may doubtless be made in various ways, I prefer to make it from

some normally stiff sheet material, which, under proper conditions, becomes somewhat plastic and, while subjecting such sheet material to the conditions necessary to make it plastic, pressing it against the surface of a shoe last of the desired contour and permitting it to set while in contact with the last so that it retains the exact shape of the last.

One material suitable for the purpose is sheet celluloid, while the substance known commercially as "bakelite" is also well adapted for the purpose. Doubtless other materials may be found which would provide the necessary qualities of lightness, resiliency, strength and capability of conforming under proper conditions to the irregular shape of a last, and I contemplate that any such materials may be employed, if desired, in making my improved form.

The side portions 6 and 7 of the improved form extend rearwardly and are overlapped at 6^a and 7^a to form the heel portion. These overlapped portions are separate and unconnected from top to bottom as indicated at 8 so that they are capable of a slight degree of relative lateral movement when the interior surface of the heel portion is subjected to lateral pressure.

A narrow slit 10, preferably of substantially uniform width, extends from the point 9 at the upper end of the cone downwardly and forwardly to the throat portion where it terminates in an opening 11 of a diameter greater than the width of the slit. This mode of terminating the slit is preferred as it forms a stop to prevent accidental extension of the slit into the lower forepart of the form.

The bottom of the form shown in Figs. 1, 2 and 3 is entirely open as indicated at 12 (Fig. 3), and the lower edges 13 are smooth and unbroken from the heel portion to the point 14 near the toe. From this point forward the edge is cut away for a purpose hereinafter more fully explained.

In Fig. 4 a slightly modified construction is shown wherein the form 15 is in general like the form shown in Figs. 1 and 2, having the heel portion 3^a and the toe portion 5^a T, but has its lower edge 13^a extending continuously from the heel to the toe and is unprovided with the slit at its cone portion.

In Fig. 5 a further modification is illustrated wherein the form 16, while preferably having the overlapping portions 6^b and 7^b at its heel end is turned inwardly along the forepart of the shoe to provide the flange 17, and a strengthening bridge 18 preferably extends across the ball of the foot from one flange to the other.

The forms shown in Figs. 4 and 5 are particularly intended for use as trees for plumping out a finished shoe either during exhibition or between intervals of use although they may well be employed during

the manufacture of a shoe if introduced at a stage in the operation such that they may be removed without difficulty at a later time, or such that they do not interfere with operations upon the shoe sole.

The form shown in Figs. 1 and 2 is particularly intended for use in my improved shoe making process above outlined in accordance with which the form is placed upon the last prior to the lasting operation. The proportions of the parts are such that when thus placed upon a last the edge 13 of the form is flush with the lower surface of the innersole. The upper is now lasted over the combined form and last and after the lasting operation is complete, if, for example a McKay shoe is being made, the last is withdrawn leaving the form within the shoe and the form remains in the shoe during all subsequent operations.

In withdrawing the last the form is free to expand to the necessary extent in a lateral direction at its heel portion since the parts 6^a and 7^a are not connected, and likewise may expand to some extent at its cone portion by reason of the slit 10. Although the form is outwardly expansible at its heel it is not so readily pressed inwardly since the overlapping portions tend to interlock and prevent such inward movement. Since in almost all cross sections the form presents a curved contour it has a strong arching effect which makes it capable of withstanding a very substantial crushing pressure and it has been found in actual practice that it is capable of withstanding to the necessary degree all of the various forces which may be brought to bear upon it during the process of making the shoe.

When the shoe is completed as indicated in Fig. 6 where the forepart of the shoe is indicated at F and the heel portion at H, the form 1 may if desired be withdrawn from the shoe, the cutaway portion forward of the point 14 of the form facilitating such withdrawal since the edge of the form forward of the point does not engage with the edge of the innersole.

While I may, in accordance with my aforesaid process, withdraw the form at the completion of the shoe I may alternatively permit the form to remain in the shoe until it is placed in the hands of the ultimate consumer. In the latter event I prefer to trim off the upper projecting portion of the form along a line such as indicated at 19 in Fig. 6, so that the upper edge of the form will be flush with the upper edge of the shoe. Thus, without detracting from the appearance of the shoe or adding materially to its weight the shoe may be kept plumped out and in exactly the shape which was imparted to it in lasting until it is placed in the hands of the consumer, and if desired the latter may employ the form dur-

ing intervals between use as a shoe tree for keeping the shoe in proper shape.

While I have illustrated several modified constructions I contemplate that the invention may be embodied in other specific arrangements and that other uses may be found for the form, such for example as its employment as a protecting cover for the outer surface of a shoe during the process of manufacture. In the latter case a form substantially as shown in Fig. 4 would probably be employed, suitable fastener means being provided for attaching it although such fastener means would not be absolutely necessary and I contemplate that under some circumstances the edges of the form might be lasted in with the upper to retain the form in position. In this case if the substance of the form were of such character as to make this operation difficult I contemplate the provision of a margin or border secured to the edge of the form and capable of being lasted in with the upper, such marginal portion in any case being cut off to release the form at the completion of the shoe.

While I have not described in detail the mode of making this form it is to be understood that it may be made in any suitable manner and by the use of any suitable machinery.

While the form as made of the materials which I have referred to as desirable, is very thin so that it does not add materially to the size of the last, I propose if necessary, to employ with the form a last slightly smaller than the desired size of the shoe, for example, a half size smaller, or possibly subjecting the last to a shrinking operation so as to reduce its size to compensate for the added thickness of the form.

While the form having the overlapping portions at its rear end is preferred, such overlapping parts may be dispensed with and a simple slit or fissure provided at this point, and when the form is to be inserted in a shoe after the last has been withdrawn I find that it is not entirely necessary to provide for capability of expansion either at the heel portion or the toe portion, in which event the heel parts may be integrally or otherwise united and the slit 10 may be omitted.

I claim:

1. A hollow form for insertion into a completed or partly completed shoe, said form having substantially the shape of the external contour of a shoe last and comprising toe and heel portions, the space within the form being substantially unobstructed and capable of receiving a last, the form being open at its top to permit a last to be withdrawn therefrom or reinserted therein, said form having thin and stiffly resilient walls of waterproof material and being open over

the major portion at least of its bottom and normally closed at its heel end.

2. A hollow form for insertion into a completed or partly completed shoe, said form consisting of thin celluloid shaped to fit snugly within a shoe and comprising toe and heel portions, the space within the form being capable of receiving a shoe last, the form being open at its top to permit a last to be withdrawn therefrom or reinserted into the space within the form and being normally closed at its heel end.

3. A thin walled hollow shoe form open at top and bottom and having substantially the shape of a shoe last, said form comprising a toe portion, the lower edge of the form being cut away around the toe portion thereof to facilitate withdrawal of the form from a finished shoe.

4. A hollow shoe form having substantially the external contour of a shoe last, said form comprising heel and toe portions and being open at its top and bottom, the walls of the form being thin and stiff, the toe portion being adapted to extend to the extreme forward end of the cavity in the shoe, the lower edge of said toe portion being cut away to facilitate withdrawal of the form from the shoe.

5. A thin walled hollow shoe form permanently open at the top and having the shape of a shoe last and comprising a heel portion, said heel portion being of double the thickness of the remainder of the form and being laterally expandable from top to bottom when subjected to lateral pressure applied to its inner surface and being shaped to resist pressure applied to its outer surface.

6. A thin walled hollow shoe form permanently open at the top and having substantially the shape of a shoe last and comprising forepart and heel portions, the heel portion comprising curved overlapping elements which are unconnected from top to bottom but adapted to resist inwardly directed pressure.

7. A hollow open-topped shoe form having the shape of a shoe last, said form comprising toe and heel portions, the walls of the form being thin and stiffly resilient, the heel portions of the form comprising overlapping parts unconnected from top to bottom.

8. A hollow form adapted to be inserted in a finished shoe, said form consisting of thin and stiff sheet material molded to shape and comprising side walls which are turned inwardly at the heel portion of the form to constitute overlapping plies.

9. A hollow form adapted to be inserted in a finished shoe, said form consisting of sheet celluloid molded to shape, the side walls being overlapped at the heel to reinforce the latter, the overlapping portions

being free and unconnected from top to bottom of the heel.

10. An open topped hollow shoe form having substantially the shape of a shoe last, said form having thin walls constituting fore part and side portions, the latter extending rearwardly and overlapping to form the heel portion, said overlapping parts being unconnected from top to bottom and relatively movable.

11. A hollow shoe form permanently open at its top and having the shape of a shoe last, said form comprising a fore part, side, and heel portions, the fore part having a narrow slit of substantially uniform width

extending from its upper edge forwardly toward its throat portion.

12. A thin walled hollow shoe form permanently open at its top and having substantially the shape of a shoe last, said form comprising a forepart portion, said forepart portion having a narrow slit extending forwardly from its upper edge to its throat, said slit terminating in an opening of a diameter greater than the width of the slit.

Signed by me at Auburn, New York, this 12th day of June, 1925.

WILLIAM J. DE WITT.
